CLAIM

The ornamental design for transitional graphic user interface for a display of a mobile telephone, as shown and described.

DESCRIPTION

FIG. 1 is a front view of a first image of a transitional graphic user interface for a display of a mobile telephone showing our design; and,

FIG. 2 is a front view of a second image thereof.

The broken line showing of the display of a mobile telephone, text and images in both views forms no part of the claimed design.
